UNITED STATES PATENT OFFICE.

WILLIAM C. WATKINS, OF NEW HAVEN, CONNECTICUT.

ARCTIC-BUCKLE.

1,148,132.

Specification of Letters Patent. Patented July 27, 1915.

Application filed March 12, 1915. Serial No. 13,993.

To all whom it may concern:

Be it known that I, WILLIAM C. WATKINS, a citizen of the United States, residing at New Haven, in the county of New Haven 5 and State of Connecticut, have invented a new and useful Improvement in Arctic-Buckles; and I do hereby declare the following, when taken in connection with the accompanying drawings and the characters of 10 reference marked thereon, to be a full, clear, and exact description of the same, and which said drawings constitute part of this application, and represent, in—

Figure 1 a plan view of an arctic buckle 15 constructed in accordance with my invention and shown as applied to the flaps of an arctic. Fig. 2 a longitudinal sectional view of the same in the closed or locked position. Fig. 3 a similar view showing the hook 20 turned in position to be disengaged from the ladder. Fig. 4 a plan view of the ladder, detached. Fig. 5 a plan view of the hook, detached.

This invention relates to an improvement 25 in arctic buckles which usually consist of a ladder and a clasp, the clasp usually being formed in two or more parts.

The object of this invention is to form the 30 clasp or hook member in a single piece so that it can be more conveniently engaged and disengaged from the ladder, as well as 35 reduce the cost of manufacture; and the invention consists in the construction herein-after described and particularly recited in the claims.

In carrying out my invention I employ the usual ladder 2 except it will be noted that the outer ends 3 are rounded to prevent the 40 end of the ladder from chafing an arctic to which it is applied. The rear end of the ladder is provided with the usual loop 4 by which it is attached by a flexible strap 5 to one side 6 of an arctic. The ladder is also formed with the usual openings 7 forming a 45 series of intermediate bars 8. The hook member is formed from a single piece of metal and comprises a bar 9 by which the hook member may be attached by a flexible strap 10 to the other side 11 of the arctic and 50 in line with the ladder 2. The rear portion 12 of the hook forms a finger-piece by which

the hook may be turned. The outer end 13 of the hook is turned downward and rearward, and part of the metal forward of the bar 9 being removed forms a bill 14 which 55 points rearward and is adapted to engage with the bars 8 of the ladder. It is to be noted that the length of this bill corresponds substantially to the width of the openings 7 in the ladder. The ladder is bowed longitudinally and is adapted to pass between the bill 14 and the bar 9 and so as to extend beneath the flap 11 of the arctic. When the flaps are drawn together to the desired extent, the bill 14 is passed up through one of 60 the openings 7 and allowed to engage with one of the bars 8.

To disengage or readjust the buckle, it is only necessary to slightly raise the finger-piece which is permitted by the flexible strap 70 10 so as to move the bill away from the bar with which it engages and allow it to pass through the opening. The ladder is then free to be moved back or forth between the bill 14 and the bar 9. It will thus be seen 75 that I provide an arctic buckle with a one-piece hook which is more convenient in fastening and unfastening the arctic than is a two-part clasp.

I claim:—

1. An arctic buckle comprising a ladder having a series of alternating bars and openings, a one-part hook comprising a bar, a finger-piece a downwardly and rearwardly extending hook, and a rearwardly extending 85 bill adapted to pass through the openings in the ladder and engage with the bars thereof.

2. An arctic buckle comprising a ladder provided with alternating openings and bars, and a hook provided with a bar, a rearwardly extending finger-piece, a downwardly and rearwardly extending hook, and a rearwardly extending bill corresponding in length to the width of the slots in the ladder and adapted to engage with the bars thereof. 95

In testimony whereof, I have signed this specification in the presence of two subscribing witnesses.

WM. C. WATKINS.
